UNITED STATES PATENT OFFICE.

HUGH W. HARRIS, OF ATLANTA, GEORGIA, ASSIGNOR TO UNDERWOOD TYPEWRITER COMPANY, OF NEW YORK, N. Y., A CORPORATION OF DELAWARE.

TYPEWRITING MACHINE.

Application filed October 12, 1920. Serial No. 418,371.

To all whom it may concern:

Be it known that I, HUGH W. HARRIS, a citizen of the United States, residing in Atlanta, in the county of Fulton and State 5 of Georgia, have invented certain new and useful Improvements in Typewriting Machines, of which the following is a specification.

The present invention relates to typewriting machines having sets of feed-rolls arranged one forward of the other in line-space direction relatively to the platen, so that a plurality of superposed work-sheets with interleaved carbon-sheets may be 10 gripped and fed between the feed-rolls and the platen, and in which the work-sheets may comprise as a first or top sheet a narrow statement-sheet, and as a second sheet a wider ledger-sheet projecting at its opposite 15 margins beyond the statement-sheet, and as a third sheet a proof-sheet underlying the ledger-sheet and which may be wider and project at its opposite margins beyond the ledger-sheet. More particularly, the present 20 invention relates to means for relatively positioning or collating the several work-sheets after these work-sheets have been inserted around the platen between the platen and the feed-rolls.

30 The present invention is a further development of the paper-feeding mechanism disclosed in my Patent No. 1,294,456, of February 18, 1919; and also of the typewriting machine forming the subject of my pending application for patent, serial No. 333,304, filed October 25, 1919. Also my present invention is herein disclosed as embodied in a typewriting machine in which the mechanism for supporting and casting off the 35 feed-rolls is generally similar to that disclosed in the patent to Helmond, No. 1,058,672, of April 8, 1913.

The broad idea involved in the present invention, and also in my above-noted prior 45 inventions, relates to means for holding certain selected work-sheets stationary, while other work-sheets are fed relatively thereto either forward or backward by rotating the platen; for example, holding a statement-sheet stationary while an underlying wider ledger-sheet is adjusted relatively to the 50 statement-sheet, and also holding both the statement-sheet and ledger-sheet stationary while a proof-sheet nearer the platen is adjusted relatively to the statement-sheet and

ledger-sheet, whereby relative adjustment of all three sheets may be effected. In the construction disclosed in my above-noted Patent No. 1,294,456, this result is accomplished by means of mechanism for selectively locking feed-rolls which are in contact with the work-sheets which are to be held stationary. In the construction disclosed in my above-noted application serial No. 333,304, a similar result is accomplished by means of 60 mechanism for selectively casting off feed-rolls from the work-sheets which are to be held stationary while other work-sheets on the platen are adjusted relatively thereto, frictional holding devices being pressed 65 against the work-sheets which are to be held stationary. 70

According to the present invention as herein disclosed, front and rear feed-rolls are offset relatively to each other in the direction of the length of the platen, so that one of these feed-rolls will engage the narrow top sheet while the other of these rolls will engage the projecting margin of a wider underlying sheet, so that by casting off the 75 feed-roll from the narrower top sheet the wider underlying sheet may be fed forward or backward by the platen relatively to the top sheet, and by casting off both feed-rolls 80 another underlying sheet nearer to the platen may be adjusted relatively to the two outer sheets. More particularly, according to the present invention as herein disclosed, a rear complete or continuous set of axially-aligned feed-rolls has its inner rolls engageable 85 with the narrower outer or top sheet, its outer rolls being engageable with the laterally projecting margins of an underlying wider sheet; and a front set of axially-aligned feed-rolls has the feed-rolls thereof 90 axially spaced so as to engage only the laterally projecting margins of the wider underlying sheet, leaving the narrower top sheet free to pass opposite the open space between these spaced forward feed-rolls. In this construction, when both sets of feed-rolls are in engagement, all of the superposed work-sheets and their interleaved carbons may be 95 fed in line-space direction by rotating the platen. By casting off the rear set of feed-rolls, the axially-spaced feed-rolls of the forward set will co-operate with the platen 100 to feed the wider underlying work-sheets, while leaving the narrower top work-sheet stationary. By casting off both sets of feed- 105 110

rolls, both the narrower top sheet and the wider underlying sheet may remain stationary while another underlying sheet nearer the platen may be moved with the platen in 5 line-space direction.

For assuring effective operation in the manner above noted in adjusting the several superposed work-sheets, normally ineffective frictional holding devices are provided and are actuated to the engaging position concomitantly with the casting off of the feed-rolls, thereby to hold stationary 10 the work-sheets from which the feed-rolls have been cast off.

15 Other features and advantages will hereinafter appear.

In the accompanying drawings,

Figure 1 is a front view, showing my invention embodied in a platen frame of the 20 type employed in the Underwood typewriting machine, with the several parts in normal position for typing, and in which all of the superposed work-sheets may be fed in line-spacing direction.

25 Figure 2 is an inverted plan view of what appears in Figure 1.

Figure 3 is a transverse section on a vertical plane indicated by the line 3—3 of Figure 1, as viewed from the right, and with 30 the several parts in the same or normal position, both sets of feed-rolls being in the effective position, and both sets of frictional holding devices being in the ineffective position.

35 Figure 4 is a similar view indicated by the line 4—4 of Figure 1 and shows an intermediate position of the movable parts in which the rear set of feed-rolls is cast off, and the middle set of friction members 40 in engagement with a narrow top sheet.

Figure 5 is a view similar to Figure 4, but with the movable parts at the final position, in which both sets of feed-rolls have been cast off and both sets of friction members moved to the engaging position.

45 Figure 6 is an enlarged fragmentary view similar to Figures 4 and 5, but with the movable parts shown as in the normal position shown in Figure 3.

50 A usual rotative platen 1 has an axle 2 journaled in end members 3 of a substantially usual platen-frame, comprising, besides these end members, upper and lower tie-rods 4 and 5, and an inclined paper-chute 55 or paper-table 6, which is shown as continued around below the platen 1 to form a curved paper-apron 7.

55 In the construction shown in the drawings, the platen 1 is shown as having thereon, as a first or top sheet, a comparatively narrow statement-sheet A, and, as a second sheet, a wider ledger-sheet B projecting at its opposite side margins beyond the statement-sheet A, and, as a third sheet, a yet 65 wider proof-sheet C underlying the ledger-

sheet and shown as projecting at its opposite margins beyond the ledger-sheet B, together with a narrow carbon-sheet b for the ledger-sheet B and a wider carbon-sheet c for the proof-sheet C. There is provided a rear 70 set of axially-aligned feed-rolls 8, which are co-operative with the platen through openings shown as provided in the paper-apron 7, these feed-rolls 8 being shown as four in number and as arranged to form a continuous 75 series of which the two inner feed-rolls will engage the narrow statement-sheet A, and of which the outer feed-rolls will respectively engage the projecting margins of the underlying ledger-sheet B. There is also 80 provided a front set of axially-aligned feed-rolls 9, shown as two in number spaced apart in the direction of the length of the platen 1, for thereby engaging only the projecting lateral margins of the underlying wider 85 ledger-sheet B, while leaving free the narrower statement-sheet A, which comes opposite the space between these two spaced feed-rolls.

Spring-pressed paper-fingers 10, each 90 provided with a pressure-roll 11, are adjustably mounted upon the upper tie-rod 4, and, in carrying out the present invention, these fingers 10 and their rolls 11 are positioned so as to engage the projecting margins of 95 the proof-sheet C and its carbon-sheet c, so as to assist in the adjustment of the proof-sheet C relatively to the statement-sheet A and ledger-sheet B. The four axially-aligned rear feed-rolls 8 are carried by, and 100 mounted to rotate upon, a shaft 12, and the two axially-aligned and laterally-spaced front feed-rolls 9 are similarly mounted to rotate upon the ends of a shaft 13. The rear feed-roll shaft 12 is carried by a pair 105 of lever-arms 14 pivoted on and projecting rearwardly from the tie-rod or supporting rod 5, and the forward feed-roll shaft 13 is similarly carried by a pair of lever-arms 15 110 pivoted on and projecting forwardly and upwardly from the supporting rod 5 in diverging relation to the rear lever-arms 14. The rear feed-rolls 8 are normally pressed towards and into effective co-operative relation with the platen 1 by means of a pair 115 of coiled thrust-springs 16 acting between lugs 17 formed on the lever-arms 14 and brackets 18 fixed upon the supporting rod 5, the tension of these springs 16 being adjustable by means of screws 19. Similarly, 120 the front feed-rolls 9 are normally pressed towards and into effective co-operative relation with the platen 1 by means of coiled thrust-springs 20 acting between rearwardly-projecting lugs 21 formed on the forward 125 lever-arms 15 and brackets 22 fixed on the supporting rod 5, the tension of these springs 20 being adjusted by means of screws 23. This arrangement of the spring-pressed lever-arms for the feed-rolls is substantially 130

the same as is disclosed in the above-noted patent to Helmond, No. 1,058,672. Releasing levers 24 for the feed-rolls are provided and are shown as two in number, corresponding to the pairs of lever-arms 14 and 15. Each of these releasing levers 24 is pivoted at a median point thereof on a rearwardly-projecting supporting bracket 25 fixed on the supporting rod 5, so that each of these 5 levers has a rearwardly-projecting arm and a forwardly-projecting arm. The rearwardly-projecting arm of each of these releasing levers 24 engages above the rear feed-roll shaft 12 for casting off the rear feed-rolls 8 from the platen 1. The forwardly-projecting arm of each of these releasing levers 24 has a lost-motion engagement with a pin 26 projecting laterally from the rearwardly-extending lug 21 of the adjacent lever-arm 15 10 for casting off the forward feed-rolls 9 by continued movement of the releasing levers 24 after the rear feed-rolls 8 have been cast off, so that when the releasing levers 24 are operated the rear feed-rolls 8 will be first 15 cast off, and then by further movement of these releasing levers the forward feed-rolls 9 will also be cast off from the platen 1.

The releasing levers 24 are operated to cast off the feed-rolls 8 and 9 by means of 20 an operating shaft or rock-shaft 27 provided with cams 28 engageable with the lower sides of the forwardly-projecting arms of the releasing levers 24, this rock-shaft 27 being journaled in bearings 29 fixed upon the supporting rod 5. The forward arm of each releasing lever 24 is shown as provided with an upwardly-projecting guiding toe 30. At its right end the rock-shaft 27 is provided with a downwardly-projecting crank-arm 31 25 which is connected by an inclined link 32 with a downwardly and rearwardly-projecting crank-arm 33 carried by the inner end of a short shaft 34 journaled on the adjacent end member 3 of the platen-frame, the outer 30 end of this shaft 34 having fixed thereon an upwardly and forwardly extending finger-piece 35, for casting off both sets of feed-rolls 8 and 9, to provide for inserting the several superposed work-sheets, such as A, B and C, around the platen 1. By depressing the upstanding finger-piece 35, the operating shaft 27 will be rocked in a clockwise direction as seen in Figures 3, 4, 5 and 6, and as viewed from the right in Figures 1 35 and 2, and the rear feed-rolls 8 and the forward feed-rolls 9 will be successively cast off in the order named. Excepting for the lost-motion connection between the releasing levers 24 and the pins 26, the above- 40 described cast-off mechanism is substantially the same as that disclosed in the above-noted patent to Helmond, No. 1,058,672. It is also evident that, with the finger-piece 35 at an intermediate position, the rear feed-rolls 8 45 would be cast off, while, by reason of the

lost-motion connection between the releasing levers 24 and the pins 26, the forward feed-rolls 9 would be left in the effective position. For accomplishing this last-named result, together with other results, an additional 70 mechanism, co-operative with the cast-off mechanism and including frictional sheet-holding devices, is provided and will now be described.

A pair of inner friction-members 36 is 75 provided for effectively holding the narrower statement-sheet A stationary while the underlying wider ledger-sheet B and proof-sheet C are adjusted relatively to the statement-sheet A by rotating the platen 1. 80 These friction-members 36 may be of rubber or other suitable material and are carried by the forward ends of curved spring fingers 37 the rear ends of which are secured to the paper-apron 7. These spring fingers 85 37 normally hold the friction-members 36 at an ineffective position, out of contact with the statement-sheet A, as shown in Figures 1, 2 and 4. A pair of outer friction-members 90 38, similar to the inner friction-members 36, is provided for engaging the projecting margins of the ledger-sheet B, for holding this sheet stationary while the proof-sheet C nearer the platen is adjusted by the platen forward or backward relatively to 95 both the ledger-sheet B and the statement-sheet A. These outer friction-members 38 are carried by the forward ends of curved spring fingers 39, similar to the fingers 37, and similarly secured at their rear ends to 100 the paper-apron 7, these spring fingers 39 normally holding the outer friction-members 38 at the ineffective position, out of engagement with the projecting margins of the ledger-sheet B, as shown in Figures 1, 2 and 105 3 of the drawings. The inner spring fingers 37 are engaged by corresponding inner cams 40, shown as in the form of eccentrics, and the outer spring fingers 39 are engaged by similar cams 41, all of these cams 40 and 41 110 being fixed upon a cam-shaft 42 journaled in supporting brackets 43 fixed upon the bearings 29 on the supporting rod or tie-rod 5. The inner cams 40 are so timed relatively to the outer cams 41 that, when the 115 cam-shaft 42 is rocked in a clockwise direction, as viewed from the right in Figures 1 and 2, and as appears in Figures 3, 4, 5 and 6, the inner cams 40 will first actuate the inner spring fingers 37 to move the inner 120 friction-members 36 into frictional holding engagement with the narrower statement-sheet A, and subsequently the outer cams 41 will actuate the outer spring fingers 39 to move the outer friction-members 38 into 125 effective frictional holding engagement with the projecting margins of the ledger-sheet B, while the inner friction-members 36 are still maintained in engagement with the statement-sheet A.

At its right end, the cam-shaft 42 for the friction-members is provided with an up-standing crank-arm 44, which by means of a bent link 45 is connected to a downwardly and rearwardly-extending crank-arm 46 carried by the inner end of a short shaft 47 which is journaled on the adjacent frame member 3, and which at its outer end is provided with an upwardly and forwardly-extending finger-piece 48. The short shaft 47 is located at the rear of the similar short shaft 34, and the auxiliary or second finger-piece 48 extends above and at its free end overlaps upon the first-mentioned finger-piece 35, so that the free end of the first-mentioned finger-piece 35 lies in the path of the free end of the finger-piece 48, as shown in Figures 1 to 5, inclusive, of the drawings. The last-mentioned finger-piece 48, together with the above-described parts operated thereby, may be retained at any one of three different positions, comprising an initial position, an intermediate position and a final position, by means of a detent-device shown as a leaf-spring 49 provided with indentations 50 for engaging a corresponding projection on the operating crank-arm 46, this detent-spring 49 being supported on the adjacent frame member 3 by means of a screw 51, shown in Figure 2.

Finger-wheels 52 are provided on the outer ends of the platen-axle 2 for conveniently rotating the platen 1 to insert the superposed work-sheets and also for collating or adjusting these sheets relatively to each other by means of the above-described construction. The superposed collated work-sheets may be fed in line-space direction, in writing, by means of a suitable line-spacing mechanism including a line-space wheel 53 fixed on the platen-axle 2, as shown at the left in Figures 1 and 2.

In the normal or typewriting position of the several above-described movable parts, illustrated in Figures 1, 2, 3 and 6, both of the finger-pieces 35 and 48 are in the elevated position shown in Figure 3, with both sets of feed-rolls 8 and 9 in the effective position, and with both sets of friction-members 36 and 38 at the disengaged or ineffective position, this being the initial position of the second finger-piece 48. When the second finger-piece 48 is moved from this initial position to the intermediate position thereof, shown in Figure 4, where it will be retained by the detent-spring 49, by reason of the fact that the outer free end of the first-mentioned finger-piece 35 is in the path of the outer free end of the second finger-piece 48, this last-mentioned finger-piece will engage the first finger-piece 35 and depress the latter also to an intermediate position. When the second finger-piece 48 is depressed to this intermediate position, the rear set of feed-rolls 8 will be cast off, and

concomitantly the middle or intermediate set of friction-members 36 will be moved into engagement with the top or statement-sheet A, the front feed-rolls 9 being left in the effective position, and the outer friction-members 38 being left in the ineffective position. In this intermediate position of the parts, the ledger-sheet B may be collated or adjusted relatively to the statement-sheet A merely by rotating the platen 1 forward or backward, as may be required. After this, the second finger-piece 48 may be depressed to the final position thereof, shown in Figure 5, thereby casting off also the forward feed-rolls 9 and concomitantly moving the outer set of friction-members 38 into engagement with the margins of the ledger-sheet B. In this final disposition of the movable parts, both sets of feed-rolls are in the cast-off position and both sets of friction-members are in the engaging position. By rotating the platen 1, the proof-sheet C may now be collated or adjusted relatively to the previously-collated ledger-sheet B and statement-sheet A, so that when this last collating operation is completed the three work-sheets A, B and C will be in correct collated relation. By now pushing forward the first finger-piece 35, this finger-piece will carry with it the second finger-piece 48, and all of the parts will be returned to the original normal or typing position thereof, shown in Figures 1, 2 and 3, and writing upon the collated sheets may proceed. The top or statement-sheet A may be adjusted to the correct position for writing either before or after the several sheets have been collated as above described. To accomplish this result, the first finger-piece 35 may be moved from the initial position thereof, shown in Figure 3, to the final position thereof, shown in Figure 5, without operating the second finger-piece 48, which, therefore, will be left in its initial position, appearing in Figure 3, thereby casting off all of the feed-rolls while still leaving all of the friction-members in the disengaged position, whereby all of the work-sheets may be moved with the platen, both for originally inserting the work-sheets and for bringing the top sheet A into the correct position for type-writing thereon. The first finger-piece 35 will be retained in this depressed position with all of the feed-rolls in the cast-off position, by reason of the shape of the operating cams 28 on the operating shaft 27, as will be clear from an inspection of Figure 5.

Variations may be resorted to within the scope of the invention, and portions of the improvements may be used without others.

Having thus described my invention, I claim:

1. In a typewriting machine, in combination, a rotative platen and collating means

- for effecting the relative adjustment around the platen of an outer statement-sheet and a ledger-sheet having its margins projecting beyond the sides of the statement-sheet, 5 said collating means comprising a pair of friction-members, at the front of the platen and below the printing line, supported adjacent the statement-sheet but normally out of engagement therewith, front feed-rolls 10 to engage the margins of the ledger-sheet, rear feed-rolls to engage the statement-sheet, cast-off means to release said rear feed-rolls and subsequently to release said front feed-rolls, a finger-piece, and means actuated by 15 said finger-piece to move said friction-member into engagement with said statement-sheet and to release the rear feed-rolls.

2. In a typewriting machine, in combination, a rotative platen and collating means 20 for effecting the relative adjustment around the platen of an outer statement-sheet and a ledger-sheet having its margins projecting beyond the sides of the statement-sheet, said collating means comprising a pair of 25 friction-members to engage the statement-sheet at its edges to hold the same against movement around the platen, spring-fingers on which said friction-members are mounted and by which the latter are normally held 30 clear of the statement-sheet, a finger-piece, finger-piece-actuated means for engaging said fingers and flexing the same so as to press the friction-members thereon against the statement-sheet to hold the same against 35 movement during a shifting of the ledger-sheet relative thereto, front feed-rolls to engage the margins of the ledger-sheet, rear feed-rolls to engage the statement-sheet, and means whereby actuation of said finger-piece to press the friction-members against the statement-sheet will cause the front feed-rolls to be cast off.

3. In a typewriting machine, in combination, a rotative platen, feed-rolls arranged 45 one forward of the other in line-space direction relatively to the platen, means for yieldingly pressing the feed-rolls towards the platen so that work-sheets may be gripped and fed between the feed-rolls and the 50 platen, manually-operable means including a finger-piece movable from an initial position to intermediate and final positions for successively casting off from the platen first the rear and then the front feed-roll, and a 55 detent-device for retaining said finger-piece at its intermediate position.

4. In a typewriting machine, in combination, a rotative platen to receive a plurality of superposed work-sheets diminishing in 60 width from the platen outward so that the margin of a wider underlying sheet will project laterally beyond a narrower top sheet, feed-rolls arranged one forward of the other in line-space direction relatively to the 65 platen and offset laterally in the direction of the length of the platen so that one of said feed-rolls will engage the narrower top sheet and the other of said feed-rolls will engage the projecting margin of the wider underlying sheet, means for yieldingly pressing said feed-rolls towards and into effective feeding relation with the platen, and a cast-off device for moving the feed-roll for the narrower top sheet to an ineffective position relatively thereto while leaving the feed-roll for the wider underlying sheet in the effective position in engagement with the margin thereof.

5. In a typewriting machine, in combination, a rotative platen to receive a plurality of superposed work-sheets diminishing in width from the platen outward so that the margin of a wider underlying sheet will project laterally beyond a narrower top sheet, feed-rolls arranged one forward of the other in line-space direction relatively to the platen and offset laterally in the direction of the length of the platen so that one of said feed-rolls will engage the narrower top sheet and the other of said feed-rolls will engage the projecting margin of the wider underlying sheet, means for yieldingly pressing said feed-rolls towards and into effective feeding relation with the platen, and manually-operable means for successively casting off to ineffective position first the feed-roll for feeding the narrower top sheet and then the feed-roll for feeding the wider underlying sheet.

6. In a typewriting machine, in combination, a rotative platen to receive a plurality of superposed work-sheets diminishing in width from the platen outward so that the margin of a wider underlying sheet will project laterally beyond a narrower top sheet, feed-rolls arranged one forward of the other in line-space direction relatively to the platen and offset laterally in the direction of the length of the platen so that one of said feed-rolls will engage the narrower top sheet and the other of said feed-rolls will engage the projecting margin of the wider underlying sheet, means for yieldingly pressing said feed-rolls towards and into effective feeding relation with the platen, a cast-off device for moving the feed-roll for the narrower top sheet to an ineffective position relatively thereto while leaving the feed-roll for the wider underlying sheet in the effective position in engagement with the margin thereof, a normally ineffective friction-member engageable with the narrower top sheet for holding the same stationary while the wider underlying sheet is fed forward or backward by the platen, and manual means for concomitantly actuating said cast-off device and moving said friction-member into engagement with the said narrower top sheet.

7. In a typewriting machine, in combination,

- tion, a rotative platen to receive a plurality of superposed work-sheets diminishing in width from the platen outward so that the margin of a wider underlying sheet will project laterally beyond a narrower top sheet, feed-rolls arranged one forward of the other in line-space direction relatively to the platen and offset laterally in the direction of the length of the platen so that one of said feed-rolls will engage the narrower top sheet and the other of said feed-rolls will engage the projecting margin of the wider underlying sheet, means for yieldingly pressing said feed-rolls toward and into effective feeding relation with the platen, cast-off means for successively casting off to ineffective position first the feed-roll for feeding the narrower top sheet and then the feed-roll for feeding the wider underlying sheet, a normally ineffective friction-member movable into frictional engagement with the narrower top sheet to hold the same stationary while the wider underlying sheet is fed forward or backward by the platen, a similar normally ineffective friction-member movable into frictional engagement with the projecting margin of the wider underlying sheet for holding this sheet also stationary while another sheet underlying this said wider sheet is fed forward or backward by the platen, and manually-operable means including a finger-piece for successively operating said friction-members concurrently with the cast-off means in such manner that the friction-member for the said narrower top sheet will be moved to effective position concomitantly with the casting off of the feed-roll from this sheet, and that the friction-member for the said underlying wider sheet will be moved to effective position concomitantly with the casting off of the feed-roll from this said wider underlying sheet.
8. In a typewriting machine, in combination, a rotative platen to receive a plurality of superposed work-sheets diminishing in width from the platen outward so that the margin of a wider underlying sheet will project laterally beyond a narrower top sheet, feed-rolls arranged one forward of the other in line-space direction relatively to the platen and offset laterally in the direction of the length of the platen so that one of said feed-rolls will engage the narrower top sheet and the other of said rolls will engage the projecting margin of the wider underlying sheet, means for yieldingly pressing said feed-rolls towards and into effective feeding relation with the platen, manually-operable means for successively casting off to ineffective position first the feed-roll for feeding the narrower top sheet and then the feed-roll for feeding the wider underlying sheet, and a means for retaining said manually-operable means first at an intermediate position with the feed-roll cast off from said
- narrower top sheet and then at a final position with the feed-roll cast off also from said wider underlying sheet.
9. In a typewriting machine, in combination, a rotative platen to receive a plurality of superposed work-sheets diminishing in width from the platen outward so that the margin of a wider underlying sheet will project laterally beyond a narrower top sheet, feed-rolls arranged one forward of the other in line-space direction relatively to the platen and offset laterally in the direction of the length of the platen so that one of said feed-rolls will engage the narrower top sheet and the other of said feed-rolls will engage the projecting margin of the wider underlying sheet, means for yieldingly pressing said feed-rolls towards and into effective feeding relation with the platen, cast-off means for successively casting off to ineffective position first the feed-roll for feeding the narrower top sheet and then the feed-roll for feeding the wider underlying sheet, a normally ineffective friction-member movable into frictional engagement with the narrower top sheet to hold the same stationary while the platen is moved rotatively in either direction for adjusting the wider underlying sheet, a similar normally ineffective friction-member movable into frictional engagement with the projecting margin of the wider underlying sheet for holding this sheet also stationary while the platen is rotated in either direction for adjusting a third sheet underlying the two said first-mentioned sheets, manually-operable means including a finger-piece for operating said friction-members successively and concurrently with the cast-off means in such manner that the friction-member for the narrower top sheet will be moved to effective position concomitantly with the casting off of the feed-roll from this sheet, and that the friction-member for the said wider underlying sheet will be moved to effective position concomitantly with the casting off of the feed-roll from this wider underlying sheet, and a detent-device for retaining said finger-piece at an intermediate position with the feed-roll cast off from said narrower top sheet and with said friction-member in engagement with this sheet, and also at a final position with all of said feed-rolls in the cast-off position and with all of said friction-members in effective frictional engagement with the respective said sheets.
10. In a typewriting machine, in combination, a rotative platen, a rear set of axially-aligned feed-rolls co-operative with the platen, a front set of axially-aligned feed-rolls co-operative with the platen and spaced from the rear set in line-space directions, means for yieldingly pressing the said feed-rolls of both sets towards the platen and into effective relation therewith, the feed-

- rolls of one of said sets being arranged in a continuous series for feeding both narrow and wide work-sheets, and the feed-rolls of the other of said sets being spaced so as to 5 feed only work-sheets wider than the narrower top work-sheet which may pass opposite an open space provided between the feed-rolls of said last-mentioned set of feed-rolls; and a cast-off device for the said continuous 70 set of feed-rolls, whereby the wider underlying work-sheet may be fed by the platen in either direction by the said set of spaced feed-rolls in engagement therewith while the narrower top sheet may remain stationary in said open space in the said set of spaced feed-rolls which are left in engagement with the said wider underlying work-sheet.
11. In a typewriting machine, in combination, a rotative platen, a rear set of axially-aligned feed-rolls co-operative with the platen, a front set of axially-aligned feed-rolls co-operative with the platen and spaced from the said rear set in line-space direction, 20 means for yieldingly pressing the said feed-rolls of both sets towards the platen and into effective relation therewith, the feed-rolls of one of said sets being arranged in a continuous series for feeding both narrow and wide work-sheets, and the feed-rolls of the other of said sets being spaced so as to feed only work-sheets wider than the narrower top work-sheet which may pass opposite an open space provided between the feed-rolls of 25 said last-mentioned set of feed-rolls, a cast-off device operable first to cast off said continuous set of feed-rolls from all the sheets, and then to cast off the said set of spaced feed-rolls from the wider underlying sheet, a normally ineffective friction-member engageable with the narrower top sheet for holding the same stationary while the wider underlying sheet is adjusted forward or backward by rotating the platen, a pair of normally ineffective friction-members engageable with the projecting margins of the wider underlying sheet to hold the same stationary while another underlying sheet nearer the platen is adjusted forward or 30 backward relatively to the two outer sheets, means for actuating the first-mentioned friction-member into engagement with the narrower top sheet concomitantly with the casting off of the feed-rolls from this sheet, and means for actuating the said pair of friction-members into engagement with the projecting margins of said wider underlying sheet concomitantly with the casting off of the feed-rolls from this wider underlying sheet.
12. In a typewriting machine, in combination, a rotative platen, a rear set of axially-aligned feed-rolls co-operative with the platen, a front set of axially-aligned feed-rolls co-operative with the platen and spaced from the said rear set in line-space direction, means for yieldingly pressing the said feed-rolls of both sets towards the 35 platen and into effective relation therewith, the feed-rolls of one of said sets being arranged in a continuous series for feeding both narrow and wide work-sheets, and the feed-rolls of the other of said sets being spaced so as to feed only work-sheets wider than the narrower top work-sheet which may pass opposite an open space provided between the feed-rolls of 40 said last-mentioned set of feed-rolls, a cast-off device operable first to cast off said continuous set of feed-rolls from all the sheets, and then to cast off the said set of spaced feed-rolls from the wider underlying sheet, a normally ineffective friction-member engageable with the narrower top sheet for holding the same stationary while the wider underlying sheet is adjusted forward or backward by rotating the platen, a pair of normally ineffective friction-members engageable with the projecting margins of the wider underlying sheet to hold the same stationary while another underlying sheet nearer the platen is adjusted forward or backward relatively to the two outer sheets, means for actuating the first-mentioned friction-member into engagement with the narrower top sheet concomitantly with the casting off of the feed-rolls from this sheet, and means for actuating the said pair of friction-members into engagement with the projecting margins of said wider underlying sheet concomitantly with the casting off of the feed-rolls from this wider underlying sheet.
13. In a typewriting machine, in combination, a rotative platen, a rear set of axially-aligned feed-rolls co-operative with the platen, a front set of axially-aligned feed-rolls co-operative with the platen and spaced from the said rear set in line-space direction, means for yieldingly pressing the said feed-rolls of both sets towards the platen and into effective relation therewith, the feed-rolls of one of said sets being arranged in a continuous series for feeding both narrow and wide work-sheets, and the feed-rolls of the other of said sets being spaced so as to feed only work-sheets wider than the narrower top work-sheet which may pass opposite an open space provided between the feed-rolls of 45 said last-mentioned set of feed-rolls, a cast-off device operable first to cast off said continuous set of feed-rolls from all the sheets, and then to cast off the said set of spaced feed-rolls from the wider underlying sheet, a normally ineffective friction-member engageable with the narrower top sheet for holding the same stationary while the wider underlying sheet is adjusted forward or backward by rotating the platen, a pair of normally ineffective friction-members engageable with the projecting margins of the wider underlying sheet to hold the same stationary while another underlying sheet nearer the platen is adjusted forward or backward relatively to the two outer sheets, means for actuating the first-mentioned friction-member into engagement with the narrower top sheet concomitantly with the casting off of the feed-rolls from this sheet, and means for actuating the said pair of friction-members into engagement with the projecting margins of said wider underlying sheet concomitantly with the casting off of the feed-rolls from this wider underlying sheet.
14. In a typewriting machine, in combination, a rotative platen, a rear set of axially-aligned feed-rolls co-operative with the platen, a front set of axially-aligned feed-rolls co-operative with the platen and spaced from the said rear set in line-space direction, means for yieldingly pressing the said feed-rolls of both sets towards the platen and into effective relation therewith, the feed-rolls of one of said sets being arranged in a continuous series for feeding both narrow and wide work-sheets, and the feed-rolls of the other of said sets being spaced so as to feed only work-sheets wider than the narrower top work-sheet which may pass opposite an open space provided between the feed-rolls of 50 said last-mentioned set of feed-rolls, a cast-off device operable first to cast off said continuous set of feed-rolls from all the sheets, and then to cast off the said set of spaced feed-rolls from the wider underlying sheet, a normally ineffective friction-member engageable with the narrower top sheet for holding the same stationary while the wider underlying sheet is adjusted forward or backward by rotating the platen, a pair of normally ineffective friction-members engageable with the projecting margins of the wider underlying sheet to hold the same stationary while another underlying sheet nearer the platen is adjusted forward or backward relatively to the two outer sheets, means for actuating the first-mentioned friction-member into engagement with the narrower top sheet concomitantly with the casting off of the feed-rolls from this sheet, and means for actuating the said pair of friction-members into engagement with the projecting margins of said wider underlying sheet concomitantly with the casting off of the feed-rolls from this wider underlying sheet.

- 8
- wide work-sheets, and the feed-rolls of the other of said sets being spaced so as to feed only work-sheets wider than the narrower top work-sheet which may pass opposite an open space provided between the feed-rolls of said last-mentioned set of feed-rolls, a cast-off device operable first to cast off said continuous set of feed-rolls from all the sheets, and then to cast off the said set of spaced feed-rolls from the wider underlying sheet, and means for retaining said cast-off device at an intermediate position with the set of feed-rolls cast off from said narrower top work-sheet and the other set of feed-rolls in engagement with the margins of the underlying wider work-sheet, and also for retaining said cast-off device at a final position with both of said sets of feed-rolls in the cast-off position.
15. In a typewriting machine, in combination, a rotative platen, a rear set of axially-aligned feed-rolls co-operative with the platen, a front set of axially-aligned feed-rolls co-operative with the platen and spaced from the said rear set in line-space direction, means for yieldingly pressing the said feed-rolls of both sets towards the platen and into effective relation therewith, the feed-rolls of one of said sets being arranged in a continuous series for feeding both narrow and wide work-sheets, and the feed-rolls of the other of said sets being spaced so as to feed only work-sheets wider than the narrower top work-sheet which may pass opposite an open space provided between the feed-rolls of said last-mentioned set of feed-rolls, a cast-off device operable first to cast off said continuous set of feed-rolls from all the sheets, and then to cast off the said set of spaced feed-rolls from the wider underlying sheet, a normally ineffective friction-member engageable with said narrower top sheet for holding the same stationary while the wider underlying sheet is adjusted forward or backward by rotating the platen, a pair of normally ineffective friction-members engageable with the projecting margins of the wider underlying sheet to hold the same stationary while another underlying sheet nearer the platen is adjusted forward or backward relatively to the two outer sheets, means for actuating the first-mentioned friction-member into engagement with the narrower top sheet concomitantly with the casting off of the feed-rolls from this sheet, means for actuating the said pair of friction-members into engagement with the projecting margins of said wider underlying sheet concomitantly with the casting off of the feed-rolls from this said wider sheet, manual operating means for concurrently operating the cast-off device and the actuating means for the friction-members, and a detent-device for retaining said operating means at an intermediate position with the feed-rolls cast off from said narrower top sheet and with the corresponding friction-member in engagement with this sheet, and also for retaining said operating means at a final position with both sets of feed-rolls cast off and with the said pair of friction-members in engagement with the projecting margins of said wider sheet.
16. In a typewriting machine, in combination, a rotative platen to receive a plurality of superposed work-sheets diminishing in width from the platen outward, and which may comprise as a first or top sheet a narrow statement sheet, and as a second sheet a wider ledger sheet projecting at its opposite side margins beyond the statement sheet, a rear set of axially-aligned feed-rolls co-operative with the platen and engageable with the statement sheet and with the projecting margins of the ledger sheet, a front set of axially-aligned feed-rolls co-operative with the platen and spaced in line-space direction from said rear set and axially spaced to engage the projecting margins of the ledger sheet beyond the statement sheet while leaving the latter free, and manually-operable means for casting off the rear set of feed-rolls to ineffective position while leaving the front set of feed-rolls in effective engagement with the margins of the ledger sheet, whereby by rotating the platen either forward or backward the ledger sheet may be adjusted relatively to the statement sheet.
17. In a typewriting machine, in combination, a rotative platen to receive a plurality of superposed work-sheets diminishing in width from the platen outward, and which may comprise as a first or top sheet a narrow statement sheet, and as a second sheet a wider ledger sheet projecting at its opposite side margins beyond the statement sheet, and as a third sheet a proof sheet underlying the ledger sheet, a rear set of axially-aligned feed-rolls co-operative with the platen and engageable with the statement sheet and with the projecting margins of the ledger sheet, a front set of axially-aligned feed-rolls co-operative with the platen and spaced in line-space direction from said rear set and axially spaced to engage the projecting margins of the ledger sheet beyond the statement sheet while leaving the latter free, and a manually operable cast-off device for successively casting off first the rear set of feed-rolls and then by further movement the front set of feed-rolls, whereby when both sets of feed-rolls are cast off the underlying proof sheet may be adjusted forward or backward relatively to the ledger sheet and statement sheet by rotating the platen.
18. In a typewriting machine, in combination, a rotative platen to receive a plurality of superposed work-sheets diminishing in width from the platen outward, and

- which may comprise as a first or top sheet a narrow statement sheet, and as a second sheet a wider ledger sheet projecting at its opposite side margins beyond the statement sheet, a rear set of axially-aligned feed-rolls co-operative with the platen and engageable with the statement sheet and with the projecting margins of the ledger sheet, a front set of axially-aligned feed-rolls co-operative with the platen and spaced in line-space direction from said rear set and axially spaced to engage the projecting margins of the ledger sheet beyond the statement sheet while leaving the latter free, a normally ineffective frictional holding device for engagement with the statement sheet to hold the same stationary, and a manually-operable device for concomitantly casting off the rear set of feed-rolls and moving the frictional holding device into engagement with the statement sheet. 10
19. In a typewriting machine, in combination, a rotative platen to receive a plurality of superposed work-sheets diminishing in width from the platen outward, and which may comprise as a first or top sheet a narrow statement sheet, and as a second sheet a wider ledger sheet projecting at its opposite side margins beyond the statement sheet, and as a third sheet a proof sheet underlying the ledger sheet, a rear set of axially-aligned feed-rolls co-operative with the platen and engageable with the statement sheet and with the projecting margins of the ledger sheet, a front set of axially-aligned feed-rolls co-operative with the platen and spaced in line-space direction from said rear set and axially spaced to engage the projecting margins of the ledger sheet beyond the statement sheet while leaving the latter free, a normally ineffective frictional holding member for the statement sheet, normally ineffective frictional holding members for the ledger sheet engageable with the projecting margins thereof, and a manually-operable device movable to an intermediate position for concomitantly casting off the rear set of feed-rolls and moving the said first-mentioned frictional holding member into engagement with the statement sheet, and movable to a final position for concomitantly casting off the forward set of feed-rolls from the margins of the ledger sheet and for moving the corresponding frictional holding members into engagement with the margins of the ledger sheet. 20
20. In a typewriting machine, in combination, a rotative platen to receive a plurality of superposed work-sheets diminishing in width from the platen outward, and which may comprise as a first or top sheet a narrow statement sheet, and as a second sheet a wider ledger sheet projecting at its opposite side margins beyond the statement sheet, and as a third sheet a proof sheet underlying the ledger sheet, a rear set of axially-aligned feed-rolls co-operative with the platen and engageable with the statement sheet and with the projecting margins of the ledger sheet, a front set of axially-aligned feed-rolls co-operative with the platen and spaced in line-space direction from said rear set and axially spaced to engage the projecting margins of the ledger sheet beyond the statement sheet while leaving the latter free, a manually-operable cast-off device for successively casting off first the rear set of feed-rolls and then by further movement the front set of feed-rolls, and means for retaining the cast-off device at an intermediate position with the rear set of feed-rolls cast off while the front set of feed-rolls remains effective, and also for retaining the cast-off device in final position with both sets of feed-rolls cast off. 25
21. In a typewriting machine, in combination, a rotative platen to receive a plurality of superposed work-sheets diminishing in width from the platen outward, and which may comprise as a first or top sheet a narrow statement sheet, and as a second sheet a wider ledger sheet projecting at its opposite side margins beyond the statement sheet, and as a third sheet a proof sheet underlying the ledger sheet, a rear set of axially-aligned feed-rolls co-operative with the platen and engageable with the statement sheet and with the projecting margins of the ledger sheet, a front set of axially-aligned feed-rolls co-operative with the platen and spaced in line-space direction from said rear set and axially spaced to engage the projecting margins of the ledger sheet beyond the statement sheet while leaving the latter free, a normally ineffective frictional holding member for the statement sheet, normally ineffective frictional holding members for the ledger sheet engageable with the projecting margins thereof, a manually-operable device movable to an intermediate position for concomitantly casting off the rear set of feed-rolls and moving the said first-mentioned frictional holding member into engagement with the statement sheet, and movable to a final position for concomitantly casting off the forward set of feed-rolls from the margins of the ledger sheet and for moving the corresponding frictional holding members into engagement with the margins of the ledger sheet, and a detent-device for retaining said manually-operable device at its intermediate and final positions, respectively. 30
22. In a typewriting machine, in combination, a rotative platen and collating means for effecting the relative adjustment around the platen of a statement-sheet, a ledger-sheet having its margins projecting beyond the sides of the statement-sheet, and a proof-sheet having its margins projecting beyond 35

the sides of the ledger-sheet, said collating means comprising a pair of friction-members to engage the statement-sheet at its edges to hold the same against movement 5 around the platen, a pair of friction-members to engage the margins of the ledger-sheet, spring-fingers on which said friction-members are mounted and by which the latter are normally held clear of the statement- 10 sheet, front feed-rolls to engage the margins of the ledger-sheet, rear feed rolls to engage the statement-sheet, a finger-piece, and means whereby movement of said finger-piece from its normal position to an intermediate position will cause the friction-members of the first-mentioned pair to be 15 pressed against the statement-sheet and the rear feed-rolls to be cast off and further movement of the finger-piece to a third position will cause the friction-members of the second-mentioned pair to be pressed against the margins of the ledger-sheet and the front feed-rolls to be cast off.

23. In a typewriting machine, in combination, a rotative platen and collating means 25 for effecting the relative adjustment there-around of a statement-sheet, a ledger-sheet having its margins projecting beyond the sides of the statement-sheet, and a proof- 30 sheet having its margins projecting beyond the sides of the ledger-sheet, said means comprising a pair of friction-members to engage the statement-sheet near its side edges, a pair of friction-members to engage the margins 35 of the ledger-sheet, leaf-springs on which said friction-members are mounted and by which the latter are normally held free of the corresponding sheets, a finger-piece, and finger-piece-actuated means to engage the 40 leaf-springs positioned at the edges of the statement-sheet and flex the same to press the friction-members thereon against the statement-sheet and then to engage the leaf-springs positioned adjacent the side edges 45 of the ledger-sheet to flex the same and press the friction-members thereon against the ledger-sheet.

24. In a typewriting machine, in combination, a rotative platen and collating means 50 for effecting the relative adjustment there-around of a statement-sheet, a ledger-sheet having its margins projecting beyond the sides of the statement-sheet, and a proof- 55 sheet having its margins projecting beyond the sides of the ledger-sheet, said means comprising a pair of friction-members to engage the statement-sheet near its side edges, a pair of friction-members to engage the margins of the ledger-sheet, all of said 60 friction-members being positioned at the front of the platen beneath the printing line, spring-fingers on which said friction-members are mounted and by which the latter are normally held free of the corresponding 65 sheets, a finger-piece, and finger-piece-

actuated means to engage the spring-fingers positioned at the edges of the statement-sheet and flex the same to press the friction-members thereon against the statement-sheet and then to engage the spring-fingers 70 positioned adjacent the side edges of the ledger-sheet to flex the same and press the friction-members thereon against the ledger-sheet.

25. In a typewriting machine, in combination, a rotative platen, a rear set of axially-aligned feed-rolls co-operative with the platen, a forward set of axially-aligned feed-rolls co-operative with the platen, a shaft on which the rear feed-rolls are mounted, a shaft on which the forward feed-rolls are mounted, a platen-frame including a support for the feed-rolls, lever-arms carrying the shaft for the rear feed-rolls and pivoted on said support, other lever-arms carrying the shaft of the forward feed-rolls pivoted on said support, springs acting on the lever-arms for the rear set of feed-rolls to press these feed-rolls towards the platen, springs acting on the lever-arms for the forward set of feed-rolls to press these forward feed-rolls towards the platen, an operating lever pivoted on said support and adapted to move outwardly away from the platen first the shaft for the rear feed-rolls 90 and then the shaft for the forward feed-rolls, for thereby successively casting off the rear and forward feed-rolls in the order named, an operating shaft journaled on said support and having a cam for actuating said 95 operating lever, and manually-operable means including a finger-piece for operating the said cam-carrying operating shaft.

26. In a typewriting machine, in combination, a rotative platen, a rear set of axially-aligned feed-rolls co-operative with the platen, a forward set of axially-aligned feed-rolls co-operative with the platen, a shaft on which the rear feed-rolls are mounted, a shaft on which the forward feed-rolls are mounted, a platen-frame including a support for the feed-rolls, lever-arms carrying the shaft for the rear feed-rolls and pivoted on said support, other lever-arms carrying the shaft of the forward feed-rolls pivoted on said support, springs acting on the lever-arms for the rear set of feed-rolls to press these feed-rolls towards the platen, springs acting on the lever-arms for the forward set of feed-rolls to press these forward feed-rolls towards the platen, an operating lever pivoted on said support and adapted to move outwardly away from the platen first the shaft for the rear feed-rolls and then the shaft for the forward feed-rolls, 105 for thereby successively casting off the rear and forward feed-rolls in the order named, an operating shaft journaled on said support and having a cam for actuating said operating lever, manually-operable means includ- 110

- ing a finger-piece for operating the said cam-carrying operating shaft, a curved paper-apron carried by the platen-frame and extending between the two sets of feed-rolls, the axially-aligned feed-rolls of the forward set being widely spaced at the middle of the length of the platen to provide for the insertion of a narrow top work-sheet around the platen between and out of engagement with the forward feed-rolls, a friction member for holding said narrow sheet stationary while underlying sheets are adjusted forward or backward by the platen, a spring-finger mounted on the paper-apron and supporting said friction member normally in ineffective position, other friction members adjacent to the ends of the platen for engaging the projecting margins of a second work-sheet wider than said top sheet for holding said second work-sheet stationary so that another work-sheet underlying said second work-sheet may be adjusted relatively to the two outer work-sheets by rotating the platen forward or backward, spring-fingers mounted on the paper-apron and supporting said last-named friction members in normally ineffective position, a cam-shaft journaled on said support, cams carried by said cam-shaft and engageable with said spring-fingers for moving said friction members to their effective positions and so timed that the friction member for the narrow top work-sheet will first be moved to effective position, and subsequently the friction members for the said second and wider work-sheet will be moved to effective position, manually-operable means including a second finger-piece for rotating the cam-shaft for thus successively rendering the said friction members effective, said first-mentioned finger-piece being operable independently of the said second finger-piece but said first-mentioned finger-piece being in the path of the said second finger-piece so as to be engaged and operated thereby, whereby said friction member for the narrow top work-sheet will be moved into effective engagement therewith concomitantly with the casting-off of the rear set of feed-rolls and the said friction members for the second and wider work-sheet will be brought into effective engagement with the projecting margins thereof concomitantly with the casting-off of the forward set of axially-spaced feed-rolls.
27. In a typewriting machine, in combination, a rotative platen, means to control the feeding thereby of a plurality of superposed work-sheets substantially centrally positioned with respect to each other and of widths progressively diminishing from the platen outwardly, comprising inner rear feed-rolls positioned to engage with a central outermost work-sheet, outer forward feed-rolls spaced in line-space direction from the said rear feed-rolls and positioned to engage with a wider second work-sheet beyond the margins of said outermost work-sheet, a manually-operable feed-roll controlling member, and means whereby movement of said controlling member to an intermediate position will cast off the said inner rear feed-rolls from effective to ineffective position and further movement of said controlling member to a final position will also similarly cast off said outer forward feed-rolls from the margins of said wider work-sheet.
28. In a typewriting machine, in combination, a rotative platen, a rear set of feed-rolls for maintaining a top work-sheet in operative relation with the platen, a set of forward laterally-spaced feed-rolls to engage the projecting margins of a second work-sheet of greater width and underlying the said top work-sheet, a friction member to engage and hold stationary the top work-sheet, a pair of friction members to engage the projecting margins of the said underlying work-sheet to hold it stationary, means for casting off the rear set of feed-rolls from the said top work-sheet and for subsequently casting off the forward set of feed-rolls from said second work-sheet, and means for placing the said first-mentioned friction member in engagement with said top work-sheet and for subsequently placing the said pair of friction members in engagement with the margins of the said second work-sheet.
29. In a typewriting machine, in combination, a rotative platen, sheet-feeding means including a laterally medially-positioned rear feed-roll for engaging a top sheet carried by the platen, laterally outwardly-spaced forward feed-rolls for engaging the projecting margins of a wider second sheet underlying the top sheet, a frictional detaining device to engage the top sheet and hold it stationary, a pair of frictional detaining devices to engage the margins of the underlying second sheet and hold it stationary, means including a finger-piece whereby said rear feed-roll will be cast off when the finger-piece is moved to an intermediate position and the said laterally spaced forward feed-rolls will be cast off when said finger-piece is further moved to a final position, and means including a second finger-piece for successively rendering the said detaining devices effective first upon the said top sheet and then upon the said underlying second sheet, said first-mentioned finger-piece being operable independently of said second finger-piece but said first-mentioned finger-piece being in the path of the second finger-piece so as to be engaged and operated thereby.
30. In a typewriting machine, in combination, a rotative platen and collating means

- for effecting the relative adjustment there-around of a statement-sheet, a ledger-sheet having its margins projecting beyond the sides of the statement-sheet, and a proof-
sheet having its margins projecting beyond the sides of the ledger-sheet, said means comprising a pair of friction-members to engage the statement-sheet near its side edges, a pair of friction-members to engage
10 the margins of the ledger-sheet, all of said friction-members being positioned at the front of the platen beneath the printing line, spring-fingers on which said friction-members are mounted and by which the latter are normally held free of the corresponding sheets, a finger-piece, and finger-piece-actuated means to engage the spring-fingers positioned at the edges of the statement-sheet and flex the same to press the friction-members thereon against the statement-sheet, and then to engage the spring-fingers positioned adjacent the side edges of the ledger-sheet to flex the same and press the friction-members thereon against the ledger-
25 sheet, said finger-piece-actuated means comprising a shaft extending transversely of said spring-fingers and cams on said shaft, individual to said spring-fingers.
31. In a typewriting machine, in combination, a platen, a rear paper-table extending down around the bottom of the platen to the front thereof below the printing line, and collating means for effecting relative adjustment around the platen of a statement-sheet, a ledger-sheet, having its margins extending beyond the side edges of the statement-sheet, and a proof-sheet having its margins extending beyond the side edges of the ledger-sheet, said collating means comprising friction-members adjacent the forward edge of said paper-table to engage
30 the statement-sheet on opposite sides of its medial line, a pair of friction-members positioned opposite the margins of the ledger-sheet, spring-fingers on the forward ends of which said friction-members are secured and by which the latter are normally held clear of the corresponding sheets, the spring-fingers being attached to the rear paper-table beneath the platen, a finger-piece, and finger-piece-actuated means for flexing said spring-fingers and pressing the corresponding friction-members against the corresponding sheets.
32. In a typewriting machine, in combination, a platen, a rear paper-table extending down around the bottom of the platen to the front thereof below the printing line, and collating means for effecting relative adjustment around the platen of a statement-sheet, a ledger-sheet having its margins extending beyond the side edges of the statement-sheet, and a proof-sheet having its margins extending beyond the side edges of the ledger-sheet, said collating means comprising friction-members adjacent the forward edge of said paper-table to engage the statement-sheet on opposite sides of its medial line, a pair of friction-members positioned opposite the margins of the ledger-sheet, spring-fingers on the forward ends of which said friction-members are secured and by which the latter are normally held clear of the corresponding sheets, the spring-fingers being attached to the rear paper-table beneath the platen, a finger-piece, and finger-piece-actuated means for flexing said spring-fingers and pressing the corresponding friction-members against the corresponding sheets, said finger-piece-actuated means comprising a shaft extending transversely of said spring-fingers and cams on said shaft, one for each of said spring-fingers.

HUGH W. HARRIS.
